US0D1006047S

(12) **United States Design Patent** (10) **Patent No.:** **US D1,006,047 S**
(45) **Date of Patent:** **** Nov. 28, 2023**

(54) **DISPLAY SCREEN OR PORTION THEREOF
WITH GRAPHICAL USER INTERFACE**

(71) Applicant: **Samsung Electronics Co., Ltd.**,
Suwon-si (KR)

(72) Inventor: **Gamin Park**, Suwon-si (KR)

(73) Assignee: **SAMSUNG ELECTRONICS CO.,
LTD.**, Suwon-si (KR)

(**) Term: **15 Years**

(21) Appl. No.: **29/829,389**

(22) Filed: **Mar. 4, 2022**

(30) **Foreign Application Priority Data**

Sep. 6, 2021 (KR) 30-2021-0042394

(51) **LOC (14) Cl.** **14-04**

(52) **U.S. Cl.**

USPC **D14/486**; D14/489

(74) Attorney, Agent, or Firm — McAndrews Held & Malloy, Ltd.

(57) **CLAIM**

The ornamental design for a display screen or portion thereof with graphical user interface, as shown and described.

DESCRIPTION

The FIGURE is a front view of a display screen or portion thereof with graphical user interface showing my new design.

The outer perimeter shown in broken lines in the FIGURE illustrates a display screen or portion thereof and forms no part of the claimed design. The dot-dash broken lines in the FIGURE define the boundaries of the claimed design and form no part thereof.

1 Claim, 1 Drawing Sheet
